L. Franklin INVENTOR
BY
Sigmund Herzog ATTORNEY

UNITED STATES PATENT OFFICE.

LOUIS FRANKLIN, OF NEW YORK, N. Y.

COMBINATION FLASH LIGHT AND TOILET ARTICLE.

Application filed March 9, 1922. Serial No. 542,284.

To all whom it may concern:

Be it known that I, LOUIS FRANKLIN, a citizen of the United States, and resident of the city of New York, in the county of 5 Kings and State of New York, have invented certain new and useful Improvements in Combination Flash Lights and Toilet Articles, of which the following is a specification.

10 The present invention relates to improvements in combination flash-lights and toilet articles.

The main object of the invention is to provide a device of the character described, 15 which is in the nature of a lady's vanity case, and more particularly one wherein an electric lamp is combined with a mirror, the elements being so arranged that the said lamp is capable of illuminating the object 20 to be viewed or observed by the aid of the mirror.

Another object of the invention is to so arrange the switch of the electric circuit that it is protected against accidental closing, whereby the life of the battery is greatly 25 prolonged.

A further object of the invention is to provide a ladies' vanity case of the type mentioned, which is simple in construction, 30 efficient in operation, durable, and capable of manufacture on a commercial scale, or in other words one which is not so difficult to make as to be beyond the reasonable cost of such a contrivance.

5 With these and other objects in view, which will more fully appear as the nature of the invention is better understood, the same consists in the combination, arrangement and construction of parts hereinafter 0 described, pointed out in the appended claims and illustrated in the accompanying drawings, it being understood that many 5 changes may be made in the size and proportion of the several parts and details of construction within the scope of the appended claims, without departing from the spirit or sacrificing any of the advantages 10 of the invention.

One of the many possible embodiments of 0 the invention is illustrated in the accompanying drawings, in which:—

Figure 1 is a plan view of a vanity case constructed in accordance with the present invention, in its open position; Fig. 2 is a 5 section taken on line 2—2 of Fig. 1; Fig. 3 is a section taken on line 3—3 of Fig. 1;

and Fig. 4 is a section taken on line 4—4 of Fig. 2.

The device comprises a casing, which is divided into a front half 10 and a rear half 60 11, united by a hinge 12. This casing may be of any suitable construction and design and is made of metal. The casing half 10 fits, preferably, over the reduced portion 13 of the casing half 11, the halves being held 65 in such engagement either by friction or by suitable locking means. Within the casing half 10 is mounted in any suitable manner a mirror 14, which abuts against its inner face and covers, preferably, the entire area of the front wall 15 of said casing half.

The casing half 11 is divided by a transverse partition 16 into two main compartments 17 and 18. The compartment 18 is 75 sub-divided, for instance, by a partition 19. The compartment 17 is closed by a cover 20 and the compartment 18 by a cover 21, both covers being hinged at 22 to the transverse partition 16. The sub-divisions of the 80 compartment 18 are adapted to hold toilet preparations and toilet articles, such as for instance face powder, rouge and powder puffs. The covers 20 and 21 may be held in closing positions by suitable locking means, 85 not shown.

Within the compartment 17 is mounted a lamp socket, comprising two metallic strips 23, which are fixed to and in electric contact with the casing half 11, they being 90 spaced apart and spirally wound, the distance between the same corresponding to the pitch of the screw-thread of the base 24 of a small electric incandescent lamp 25. The strips are somewhat resilient and do 95 not complete each an entire turn, the latter feature being clearly shown in Figs. 3 and 4 of the drawings. The lamp is screwed into the socket so formed in the ordinary manner, the strips, owing to their resiliency, 100 clamping the same and holding it in fixed position on the casing half 11. In the last-mentioned casing half is furthermore held a source of electric energy, for instance a dry battery 26, enclosed in a suitable insulating body 27. One of the terminals of this battery, denoted by the numeral 28 abuts against a metallic contact point 29 on the lamp base, said contact point being electrically connected to one end of one of the 110 leading-in wires of the lamp. The other leading-in wire is connected to the lamp base

24, and is thus in electric contact with the casing half 11.

On the cover 20 is mounted a switch 30, including a blade 31, which is pivoted at 32 to the inner face of the cover 20, the pivot extending through the said cover and having fixed to it on the opposite side a handle 33, the latter abutting against the outer face of said cover. The blade 31 is disposed in operative position to the second terminal of the battery, indicated at 34.

In alignment with the electric lamp, there is formed in the cover 20 an opening 35, through which a beam of light is cast by the lamp when the electric circuit is closed.

The operation of this device is as follows: When the switch is in the position shown in Fig. 1 of the drawings, the electric circuit is open, the blade 31 not contacting with the battery terminal 34. When not in use, the two casing halves are held in closing positions, thereby protecting the switch against accidental operation. When it is desired to use the contrivance, first the casing half 10 is swung on the hinge 12 to open position, as shown in Figs. 1 and 2 of the drawings. The electric lamp may then be lit by closing the circuit, that is to say by shifting the handle 33 in the direction of the arrow shown in Fig. 1 of the drawings until the blade 31 comes into electric contact with the terminal 34. When this is done, current flows from one terminal of the battery to the lamp, and through the same to the socket 35 and the metallic casing half 11. Through this casing half current passes to the blade 31 and thence back to the other terminal of the battery. The face of the observer, viewing the mirror, is thereby illuminated, so that observations may be made in the dark. To the toilet articles contained within the compartment 18 access may be had by shifting the cover 21 around its hinge onto the cover 20.

45 The device is capable of being made in

very small dimensions, so that it may be carried along in a pocket or in an ordinary lady's hand-bag. It is extremely simple in construction, its battery being so constructed that it fits into the circuit without the aid of special electric conductors. Replacement of the battery can be easily made by shifting the cover 20 to open position.

What I claim is:

1. A device of the character described comprising a casing divided into two halves in a plane passing between the front and rear walls thereof, a hinge uniting the two halves, a cover for one of said halves having an opening, an illuminating device within the covered casing half adapted to project light through said opening, and a mirror mounted within the coverless casing half.

2. A device of the character described comprising a casing divided into two halves in a plane passing between the front and rear walls thereof, a hinge uniting the two halves, a cover for one of said halves having an opening, an electric incandescent lamp within the covered casing half in alignment with said opening, an electric battery within said covered casing half in circuit with said lamp, a switch in said circuit mounted on said cover and including an operating handle on the exposed face of said cover, and a mirror mounted within the coverless casing half.

3. An incandescent lamp socket comprising a plurality of spaced apart spirally wound resilient metallic strips fixed in parallel relation, the distance between adjoining strips corresponding to the pitch of the screw-thread of the lamp base to be held in said socket, each strip being attached at one of its ends, its other end being free and spaced from the attached end.

Signed at New York, in the county of New York and State of New York, this 28th day of February, A. D. 1922.

LOUIS FRANKLIN,
